S. A. ROSE

CURTAIN STRETCHER

Filed March 2, 1925

INVENTOR.

BY S. A. Rose,

James J. Sheehan, ATTORNEYS.

UNITED STATES PATENT OFFICE.

SOPHIA A. ROSE, OF ELM CREEK, NEBRASKA.

CURTAIN STRETCHER.

Application filed March 2, 1925. Serial No. 12,640.

My present invention pertains to curtain stretchers and it contemplates the provision of a simple and inexpensive device through the medium of which curtains of various sizes may be readily stretched to eliminate the necessity of ironing.

The invention further contemplates the provision of a curtain stretching frame that is adjustable to various lengths and one in which hooks, pins or the like are eliminated thereby precluding the liability of injury to the hands of the user or the fabric of the curtain.

Other objects and advantageous features 15 of the invention will be fully understood from the following description and claim when read in connection with the drawings accompanying and forming part of this specification in which:

20 Figure 1 is a top plan view of my novel device showing the side boards or bars partly in section.

Figure 2 is a central vertical longitudinal section taken in the plane indicated by the 25 line 2—2 of Figure 2 and looking in the direction of the arrows.

Figure 3 is a transverse vertical section taken in the plane indicated by the line 3—3 of Figure 1 and looking in the direction of 30 the arrows.

Similar numerals of reference designate corresponding parts in all the views of the drawings.

My novel curtain stretcher comprises the 35 side bars 1 preferably four in number having equi-distantly arranged holes 2 and adapted to take into the holes 2 of the side bars are rods 3 that are rounded as indicated by 4. As clearly shown in Figures 1 and 2 the curtain C is stitched at S to form the loops L. I would have it distinctly understood that where curtains are provided with the loops L, such for instance as kitchen or bath-room curtains in which upper and lower fixture 40 rods are employed, it is unnecessary to use the stitching S to form the loops.

In the practical use of the invention I take an ordinary curtain that is generally provided with an upper loop L to receive the 50 well known curtain fixture and I stitch a similar loop or hem in the lower end of the curtain. I then pass the upper rod 3 through the upper hem and the lower rod 3 through the lower hem of the curtain. The 55 frame portion comprising the side bars 1 and the intermediate rods 3 is then adjusted

to proper length and the upper rod 3 is inserted into the upper hole of the inner side bars 1 and the lower rod 3 is then inserted into the lower hole of the outer side bars 1. 60 It will be seen, by reference to Figures 1 and 2 that the body of the curtain will lie upon the intermediate bars 3. These bars 3 are preferably arranged so that one of said bars passes through the lower openings of the 65 inner bars 1 and the other of the rods 3 passes through the upper openings of the outer bars 1. It will be apparent that the inner or intermediate bars and the position of same controls the length of the frame and 70 by merely adjusting the inner bars to various registering holes of the side bars the frame can be increased or decreased in length according to the need of the user. Unlike the ordinary run of curtain stretchers, my device 75 can be employed for wide or narrow curtains as well as long and short curtains and the adjustment for various lengths of curtain is an extremely simple operation.

The device consists of a frame and rods 80 preferably formed of wood or other material of extremely light weight in order that it may be easily handled by persons of limited strength. Moreover, the device is so constructed and arranged that the space required for storage is very limited. By merely removing the cross-rods the frame may be stored in a small space and this is not true of the ordinary well known stretchers and at the same time there is nothing in 85 my device that cannot readily and inexpensively be replaced should occasion demand. The bars 1 may be of any length and may also be provided with any number of openings 2 arranged at any desired points along 90 the length of the bars and the bars themselves may also be rounded as illustrated to prevent tearing of the hem during insertion of the rods but if desired the openings in the side bars may be of any configuration 95 whereby a bath-room curtain or the like in which round upper and lower fixture bars are preferably used may be inserted in to the openings of the side bars without the necessity of removing my upper and lower 100 bars 3 for insertion of the fixture bars after the curtain has dried.

It will be gathered from the foregoing that by the use of my device injurious hooks, pins or the like are eliminated and that the 105 elimination of such elements is a material step forward in the art, because of the fact

that in frames employing hooks and the like it is necessary, quite frequently, due to the weight of the curtain to replace the hooks or fastenings with new ones. Furthermore with my removable rods 3 the curtain does not depend upon mechanical skill to assure even hanging of a curtain when dried because my rods pull the curtain to the limit at all points, that is to say, the hem will have as much pressure on the sides as in the middle. Where hooks, pins or the like are used it is humanly impossible to adjust a curtain so that the entire width has the same amount of pressure exerted thereon. It is also apparent that absolutely no skill is necessary to adjust my novel device and to evenly stretch a curtain along its entire length. I would also have it understood that by increasing the length of the rods 3 curtains of the same length may be stretched at one and the same time irrespective of the number thereof and that each curtain will be stretched to a similar length. This is extremely important as experience has taught that it is practically impossible with devices now in use to stretch

all curtains of the same size so that they hang evenly with respect to each other.

The device is also adapted to be used as a frame for repairing torn curtains in which pressure of any desired amount may be placed upon the curtain without pulling same away from its upper fastening or rod.

Having described my invention, what I claim and desire to secure by Letters-Patent, is—

A curtain stretcher having parallel side members and cross rods, each of said members comprising an inner and an outer bar arranged in overlapped relation and each of said bars having apertures therein, the apertures in each of said bars being equally spaced whereby they are adapted to register, the said rods being disposed in parallelism between said members at and intermediate the ends thereof, the ends of said rods being positioned in said apertures and some of said rods engaging all of said bars.

In testimony whereof I have hereunto set my hand.

SOPHIA A. ROSE.
